UNITED STATES PATENT OFFICE.

LEE WHITCOMB, OF PLAINFIELD, ILLINOIS.

PISTON RING.

1,407,714.

Specification of Letters Patent. Patented Feb. 28, 1922.

Application filed March 28, 1921. Serial No. 456,444.

To all whom it may concern:

Be it known that I, LEE WHITCOMB, a citizen of the United States, residing at Plainfield, in the county of Will, State of Illinois, have invented certain new and useful Improvements in Piston Rings; and I do hereby declare the following to be a full, clear, and exact description of the invention, such as will enable others skilled in the art to which it appertains to make and use the same.

This invention relates to new and useful improvements in piston packing rings and particularly to piston packing rings for use on the pistons of explosive engines.

One object of the invention is to provide a piston packing ring of such construction that the same will insure against leaking past the piston whether placed with one end or the other uppermost, in the piston.

Another object is to provide a piston packing ring of this character whereby the use of pins for retaining the parts of the ring together is obviated.

Other objects and advantages will be apparent from the following description when taken in connection with the accompanying drawing.

In the drawing:

Figure 1 is a top plan view of a piston ring made in accordance with the invention.

Figure 2 is a bottom plan view of the ring.

Figure 3 is a vertical transverse sectional view on the line 3—3 of Figure 1.

Figure 4 is a perspective view of the inner or base section of the ring, the upper and lower sections being removed.

Referring particularly to the accompanying drawing 10 represents a split resilient spring ring which is thickest or widest at a point approximately 60° in one direction from the split 10' thereof, and thinnest or narrowest at a point diametrically opposite to the widest or thickest point.

Formed in the center of the outer curved face of the ring section 10 is a circumferentially extending rib 11 which forms the upper and lower peripheral grooves or channels 12 and 13,

respectively thereabove and therebelow. It 50 will be noted that, by reason of the ring section being wider at one point and thinner at the diametrically opposite point, that the upper channel 12 is shallower at the former point and deeper at the latter point. It 55 will also be noted that the lower channel 13 is shallowest below the point where the upper channel is deepest and deepest below the point where the upper channel is shallowest.

Seated in the upper channel 12 is a ring section 14 which is rectangular in cross section, said ring being split at 15, at a point adjacent the widest portion of the section 10, and having its widest portion at a point diametrically opposite to the split 15 and a point 60° in one direction from the split 10' of the section 10. The ring section 16 is seated in the lower channel 13 and is split, as at 17, at its narrowest portion said 60 split being disposed at a point 60° from the split in a direction opposite to that of the split 15.

What is claimed is:

A piston packing consisting of a split 75 spring ring body having its thinnest portion at approximately midway between the split and a point diametrically opposite the split, and its thickest portion diametrically opposite the thinnest portion, the outer peripheral face of the ring body being formed with an outstanding central rib which produces channels at opposite sides thereof, the channel at one side of the rib being deepest at the thinnest portion of the ring body and the opposite channel shallowest at such portion of the body, while the diametrically opposite portion of the first channel is shallowest at the thickest portion of the body and the other channel deepest at such portion, and rings in the channels.

In testimony whereof, I affix my signature, in the presence of two witnesses.

LEE WHITCOMB.
